CORKING MACHINE

Paul Wintenberger, Sable-sur-Sarthe,
Sarthe, FranceApplication March 14, 1933, Serial No. 660,740
In France March 14, 1932

8 Claims. (Cl. 226—90)

The invention relates to corking machine for bottles of the kind by which the bottle-bearer is locked as soon as the corking lever is operated.

In the devices already known the bottle-bearer 5 has to be previously adjusted to the determined height, according to height of the bottle to be corked.

The machine according to the invention, contrary to the former devices, makes it possible to 10 cork consecutively bottles from 22 cm. to 38 cm. i. e. from the smallest to the largest at present used without any previous adjustment of the bottle-bearer. It is comprising a frame, a bottle-bearer vertically slidably mounted on the frame, a 15 pliant cable or chain rotatably mounted on the frame and attached at one end to the bottle-bearer, a locking means attached to the other end of the pliant cable or chain and adapted to lock the bottle-bearer, a handle operatively connected with the pliant cable or chain so that 20 when the handle is operated the locking means secures the bottle-bearer in a fixed position determined by the height of the bottle.

In the accompanying drawings, which illustrate, 25 several embodiments of the corking-machine according to the invention:

Fig. 1 illustrates a vertical section through the axis of the machine, when in the resting position;

Fig. 2 illustrates a partial vertical section 30 through the axis of the machine, when the bottle has been put into position, but before the operating lever has been moved;

Figs. 3 and 4 which are similar to Fig. 2 illustrate the machine, first when the bottle is secured in a fixed position, then when the corking has taken place;

Fig. 5 is a section along line V—V in Fig. 3; Fig. 6 is a section along line VI—VI in Fig. 4;

Figs. 7 and 8 are views similar to Figs. 1 and 40 of a second form of the machine;

Figs. 9 and 10 are respectively a horizontal section along line IX—IX, and a vertical section along line X—X of Fig. 7;

Fig. 11 is a detailed view of the adjustable supporting apparatus of the bottle-bearer.

The frame 1 is provided with a pedestal 2, the legs 3 of which rest upon the ground. The frame 1 has on its side a guide 4 in which a slide 5, fastened on the bottle-bearer 6, can move vertically. The bottle-bearer 6 rests constantly upon the beak 7 of a cam 8 which turns about a pivot 9 and is subjected to the action of a back-drawing spring 10. To the upper part of the slide 5 55 is fastened one of the ends 11 of cable 12, that

runs over a roller 13, while the other end is attached to a counterweight 15 moving vertically in a groove 16 formed in the frame. The roller 13 is attached to the cam 17. On the cam 17, which turns about a pivot 18, is fitted a handle 19 that rests on a stop 20 as the result of the spring 21. The cam 17 acts upon a roller 22 fitted on the pivot 23 of a compressor 24 which moves in the guides 25 formed in the walls 26. Two springs 27, (Figure 6) attached to the pin 10 28 extending from the compressor 24, and to the lugs 29 on the frame 1, pull the compressor back as soon as the handle 19 is left free. Opposite the end 30 of the compressor 24, is member 31, in which there is a recess 32, the shape of which, 15 like the one on the end 30 of the compressor 24, is disposed in such a way that when the cork, that is larger than the neck of the bottle, is placed between them it can be squeezed by pressing upon the handle 19, and thrust down into the 20 neck of the bottle by the plunger 33 fitted on a slide 34 which can move vertically in the guide 35 formed by the extensions 36 of the walls 26. A spring 37, adapted to raise the plunger 33 and its 25 slide 34, is fitted around the plunger and rests against the member 31 and the shoulder of the plunger. The lower part of the member 31 is hollowed out in the middle 38 in order to prevent the cork from getting caught when it is thrust down into the neck of the bottle.

The corking of a bottle of any height by using this machine is done in the following manner:

The bottle rests upon the bottle-bearer 6 until its neck meets the lower part of the piece 31. The bottle is kept in position by the action of 35 the spring 10 on the cam 8. During this movement, the slide 5 has gone down and the counterweight 15 upwards. A cork is then placed between the compressor 24 and the piece 31; then the handle is pulled down toward the left. (Figures 3 and 4). During the movement of the handle, the cam 17 turns about the pivot 18; the roller 13 and the counterweight 15 are lowered, and the compressor 24 approaches the member 31. At a certain moment the counterweight 40 strikes against the cam 8 (Fig. 3); from that moment on the bottle-bearer is immovable. When continuing to pull down the handle 19 the cork is squeezed together to a diameter that has been adjusted smaller than that of the neck 50 of the bottle; when the handle thereafter is pressed against the slide 34 of the plunger 33, the bottle is finally corked. The handle, being released, returns to its position of rest under the action of the spring 21. During this move- 55

ment, the cam 17 turns about its pivot 18, the roller 13 moves upwards, pulling up the pliant cable 12 that lifts the counterweight 15. The cam 8 is now free and by the pressing of the bottle on the beak 7 of this cam, the cam turns, and the bottle may be taken out.

In the second form of the machine, as shown in Figs. 7 and 8, the bottle-bearer 6 has, at its rear part, the block 39 which is guided vertically by ribs 40 situated on the forward part of the sides of the frame 1, the rear face 41, of the block 39 being inclined. Against this face 41 rests the forward face 42 of the wedge 43, preferably hollowed out, which carries two tenons 44, each of which can move in the guide slots 45 in the sides of the frame 1 and slightly inclined towards the front. This wedge has a rear face 46 against which can rest the inclined face 47 of a counterweight 48, which is guided vertically by ribs 49, situated on the rear part of the sides of the frame 1. To the block 39 of the bottle-bearer 6 is fixed one of the ends of a sprocket chain 50, working over a sprocket wheel 51 placed under a cam 52 preferably by the intermediary of a frame 53. The other end of the sprocket chain is attached to the counterweight 48 by means of a bolt 54 with a threaded shank 55 and two lock-nuts 56 and 57. This method of attaching the chain 50 allows it to be held at the desired tension. Above the sprocket wheel 51 is placed a check 58, which prevents the chain 50 from escaping from the teeth of the sprocket wheel 51. As in the first form of the machine, the cam 52 is prolonged by the lever 19, turning about the pivot 18 and, when not in use, rests upon the stop 20, under the influence of spring 21. In each side of the frame 1 is a vertical slot 59 (Figure 10), in which the pin 60 slides receiving its vertical movement from the slot 61, in the cam 52 when the cam is rotated. In the slot 61 there moves also a pin 62 which is mounted between the two walls 63 (Figure 6) of the compressor 24, and which is constantly guided by the tenons 64 which move to and fro in the slots 65 in the sides of the frame 1 (Figures 6 and 10). The lower part of the slot 61 controls the sprocket wheel 51 in its vertical movement through the intermediary of the pin 60 and of the frame 53. The movement of the pin terminates in the slots 59 in the sides 50 of the frame 1. A screw 66 which comes to rest against the extension 67 of the member 31 permits the insertion of the cork to be regulated to any desired depth. One of the sides of the frame 1 carries three holes 68, 69 and 70 (Figure 11), disposed around the arc of a circle whose center is the fixed axis 71 furnished with the shoulder 72. A ring 73 turns about the axis 71 and carries a peg 74, the peg being so arranged that it may be pushed at will into any one of the holes 68, 69 and 70. Between the shoulder 72 and the ring 73 is placed a spring 75 which tends to keep the peg 74 forced in to the fullest extent. The holes 68 and 70 completely pierce the side of the frame 1, permitting the peg 74 to pass through sufficiently to limit the movement of the bottle-bearer. The hole 69, which does not traverse the side of the frame 1, prevents the action of the peg 74, and, in this position permits the successive corking of every type of bottle.

70 The corking of a bottle of any height with a machine embodying this second form of machine is accomplished as follows. The peg 74 is introduced into the hole 69; then the bottle is placed on the bottle-bearer 6 by pressing downwards until the neck is lodged in the hollow 38.

At this moment the forward face 42 of the wedge 43 comes into contact with the rear face 41 of the block 39 of the bottle-bearer 6. By lowering the handle 19, the sprocket wheel 51 is lowered, as is also the counterweight 48, which comes to rest between the rear face 46 of the wedge 43 and the ribs 49 of the frame 1. The bottle-bearer 6 is thus secured in a fixed position, the bottle can descend no further and the cork is compressed between the member 31 and the extremity 30 of the compressor 24 which is moved forward by the action of the cam 52. When the handle 19 is depressed to the point where the screw 66 comes into contact with the extension 67 of the member 31 (Fig. 8), the cork will have been forced into the neck to the required depth, according to the position which has been given beforehand to the regulating screw 66. When the handle 19 is released, the cam 52 rotates about the pivot 18 under the action of the spring 21, until it comes to rest against the stop 20; at the same time the sprocket wheel 51 rises again, pulls up the chain 50, and raises the counterweight 48. The wedge 43, which is not held any longer by the counterweight 48, leaves the bottle-bearer free to its vertical movement, thus permitting the withdrawal of the bottle.

When it is a matter of successively corking bottles of the same size the peg 74 is introduced into the hole 68; or 70 depending on the size of the bottle.

The advantages of this supplementary apparatus lies in the fact that it reduces sensibly the movement of the bottle-bearer, when it is a question of corking bottles of the same size. 35

The chief advantages of the machine according to the invention are the following:

It permits effective wedging at a constant angle, whatever the height of the bottles may be;

The wedging angle is slight, thus permitting 40 the immediate securing of the bottle-bearer in a fixed position;

The wedging is perfect, even if the contacting surfaces are greasy, regardless of the working condition of the machine; 45

This system of wedging permits the corking of bottles of all dimensions.

The principle advantage of the chain, serving to link the bottle-bearer to the counterweight, rests in the fact that it has no tendency to stretch 50 or to twist, as has a cable after a certain amount of use.

Having now particularly described and ascertained the nature of my said invention and in what manner the same is to be performed, I declare that what I claim is:

1. A corking machine for bottles comprising a frame, a bottle-bearer slidably mounted vertically on the frame, a flexible element movable over said frame and attached at one end to the bottle-bearer, a locking means attached to the other end of the flexible element and adapted to lock the bottle-bearer, a handle operatively connected with the flexible element so that when the handle is operated the locking means secures the bottle-bearer in a fixed position determined by the height of the bottle. 65

2. A corking machine for bottles comprising a frame, a bottle-bearer slidably mounted vertically on the frame, a flexible element movable over said frame and attached at one end to the bottle-bearer, a locking means attached to the other end of the flexible element and adapted to lock the bottle-bearer, corking means mounted on the frame for setting a cork in position relative 70 75

to the neck of the bottle to be corked and for pushing the cork into the neck of the bottle, including a handle operatively connected with the locking means and the corking means so that 5 when the handle is operated the locking means are first actuated and by the further operation of the handle the corking means are operated.

3. A corking machine for bottles comprising a frame, a bottle-bearer slidably mounted vertically on the frame, a flexible element movable over said frame and attached to one end to the bottle-bearer, a cam mounted on the frame for supporting the bottle-bearer, a counterweight attached to the other end of the flexible element 10 and adapted to act on the cam, a handle operatively connected with the counterweight so that when the handle is operated the counterweight holds the cam in a fixed position and thereby secures the bottle-bearer in a fixed position determined by the height of the bottle.

4. A corking machine for bottles comprising a frame, a bottle-bearer slidably mounted vertically on the frame, a flexible element movable over said frame and attached at one end to the bottle-bearer, a cam mounted on the frame for supporting the bottle-bearer, a counterweight attached to the other end of the flexible element and adapted to act on the cam, a handle operatively connected with the counterweight and the 15 corking means, so that when the handle is operated the counterweight holds first the cam in a fixed position and thereby secures the bottle-bearer in a fixed position determined by the height of the bottle and by the further operation of the 20 handle, the corking means are operated.

5. A corking machine for bottles comprising a frame, a bottle-bearer vertically and slidably mounted on the frame, having an inclined face at its rear part, a flexible element movable over 25 said frame and attached at one end to the bottle-bearer, a wedge shaped member slidably mounted

on the frame and adapted to act on the inclined face of the bottle-bearer, a counterweight attached to the other end of the flexible element adapted to act on the wedge-shaped member, a handle operatively connected to the counterweight and the bottle-bearer so that when the handle is moved the counterweight acts on the wedge shaped member so as to secure the bottle-bearer in a fixed position determined by the 30 height of the bottle.

6. A corking machine for bottles comprising a frame, a bottle-bearer vertically and slidably mounted on the frame, having an inclined face at its rear part, a flexible element movable over said frame and attached at one end to the bottle-bearer, a wedge shaped member slidably mounted on the frame and adapted to act on the inclined face of the bottle-bearer, a counterweight attached to the other end of the flexible element adapted to act on the wedge shaped member, corking 35 means mounted on the frame for setting a cork in position relative to the neck of the bottle to be corked and for pushing the cork into the neck of the bottle, a handle operatively connected to the counterweight and the bottle-bearer so that when the handle is moved the counterweight acts on the wedge shaped member so as to secure the bottle-bearer in a fixed position determined by the height of the bottle, and, by the further operation of the handle, the corking 40 means are operated.

7. A corking machine as claimed in claim 2 comprising a cam secured to the handle for actuating the locking means and the corking means.

8. A corking machine as claimed in claim 1 comprising displaceable means mounted on the frame for limiting the movement of the bottle-bearer for use when corking bottles of the same height.

P. WINTENBERGER.
